UNITED STATES PATENT OFFICE.

ALEXANDER HUREWITZ, OF BRONX, NEW YORK.

BUTTON-MAKING MACHINE.

Application filed November 30, 1926. Serial No. 151,628.

This invention relates to improvements in button-making machines, and has particular reference to a foot press mechanism therefor.

An object of the invention is to provide 5 an improved mechanism of simple and practical construction by means of which a maximum pressure upon the movable die of the machine will be obtained and which mechanism may be adjusted to regulate the effective movement of said die so that buttons of 10 different thicknesses may be produced.

Another object is to utilize the support for 15 the pressure mechanism as a means to which a part of a button ejector device may be adjustably connected and supported for proper ejection of the button from the die.

The above and other objects will appear more clearly from the following detail description, when taken in connection with the 20 accompanying drawing, which illustrates a preferred embodiment of the inventive idea.

In the drawings—

Figure 1 is a front elevation, partly in section, of the machine constructed in accordance with the invention;

Figure 2 is a fragmentary side elevation of the machine, partly broken away and shown in section; and

Figure 3 is a sectional view taken on the line 3—3 of Figure 1.

The machine of the present invention is capable of being mounted upon a suitable support 5, such as a table or the like, and consists of upper and lower frame members 35 6 and 7 connected by the standards 8. A bracket 9 is secured to the lower member 7 and is utilized to support the foot operative treadle 10 pivoted to the bracket at 11, the operative position of the treadle being shown 40 in full lines in Figure 2. It is desirable to limit the movement of the treadle to its operative position for a purpose which will appear in the course of the description and to this end there is provided a laterally extending frame 12 preferably extending from the support 5, said frame consisting of a pair of parallel rods connected at their outer ends by a cross piece 13. A sliding abutment 14 is carried between said rods and may be 45 adjusted longitudinally thereof by a screw 15 having threaded engagement with the cross piece 13. The abutment 14 is mounted in the path of movement of the lower end of

the treadle 10 so that the latter will strike against the abutment as shown in Figure 2 55 when the same is operated.

Slidable vertically upon the standards 8 is a plunger 16, the movement of which is controlled by the operation of the treadle 10 through the medium of a mechanism which will later be described. The downward movement of the plunger 16 is utilized to control the operation of the die in forming a button while the upward movement of the plunger produces the ejection of the button 60 from the die. The die consists of the upper and lower die members 17 and 18, the latter of which is mounted in a base plate 19 secured to the frame member 7. The upper die member 17 is slidable in a holder 20, the shank 21 of which is fitted within an opening 22 formed in the plunger 16 and removably secured in position therein in any desired manner as by a screw 23 extending laterally into the plunger 16 and engageable 65 with said shank. The holder 20 also carries a cutter 24 therein in which the die member 17 is also movable and this cutter is held in position in the holder by a screw 25. Positioned directly below the holder and cutter 70 is a material-supporting plate 26 having an opening therein for receiving the upper end of the lower die member 18 when the die is in its operative position, as shown in Figure 75 1. This plate 26 is yieldably supported by springs 27 and normally the upper surface of the plate is positioned slightly above the upper end of the member 18. With the plunger 16 raised a sheet of celluloid or other material of which the button is to be 80 made is laid upon the plate 26 directly below the upper die member 17 and the cutter 24 so that when the latter two members are forced downwardly with the plunger 16 the cutter will first engage the sheet of material 85 and cut therefrom the button 28. In so doing the cutter will engage the plate 26 and force the same downwardly against the tension of the springs 27. The molding surface of the upper die member 17 comes 90 in contact with the upper surface of the button 28 and thus molds the same into the desired configuration and simultaneously a pair of hole-forming points or needles 29 supported within the member 17 by a rod 100 30 are caused to penetrate the button 28 to

form openings in the center thereof. It will, of course, be understood that more than two of the points 29 may be employed, if desired. The points 29 are removably held 5 within the member 17 by the rod 30 and a ferrule 31 mounted over the lower end of said rod.

After the cutting and molding operation of the button the plunger 16 is permitted to 10 rise and in so doing the upper die member 17 is projected downwardly to eject the button 28 from within the lower end of the cutter 24, the plate 26 at the same time returning to its normal position so that the 15 remainder of the piece of material from which the button has been cut may be quickly removed from the plate 26 and another piece of material placed in position thereon. The means for causing the ejection 20 of the button consists of an ejector device comprising a disk 32 mounted within the opening 22 above the upper end of the shank 21 and having pins 33 depending therefrom and extending through said shank 25 so as to rest upon the upper end of the member 17. As the plunger 16 rises the disk 32 comes in contact with the lower end of an ejector operating rod 34, the mounting for which will later be described in detail. 30 This contact forces the ejector device and consequently the die member 17 downwardly relative to the cutter 24 and needles 29 so that the button 28 will be ejected from the cutter member and needles, the member 17 35 remaining in its projected position until the same again engages a sheet of material upon the succeeding downward movement of the plunger 16.

The mechanism for the application of 40 pressure to the plunger 16, the actuation of which is controlled by the treadle 10, will now be described. This mechanism is in the form of a toggle construction consisting of a pair of upper arms 35 pivotally mounted 45 at their upper ends upon the trunnions of a bearing block 36 and each having a pivot pin 37 extending through its lower forked end so as to pivotally connect the upper end of a lower arm 38 thereto, the lower end of each 50 of said arms 38 being in turn pivotally connected to the plunger 16 by means of the shackles 39. Each of the pins 37 has connected thereto the forked end of a link 40, the other end of which is loosely mounted 55 upon a pin 41 carried by the upper extremity of the treadle 10. Through this connection of the arms 35 and 38 with the treadle, it will be apparent when the upper extremity of the latter is raised, as shown in dotted lines in 60 Figure 2, the pivotal connections 37 between said arms will be moved laterally so as to throw the arms out of vertical alignment and thus permit the plunger 16 to be elevated, it being understood that the trunnions of the bearing block 36 form a fixed

point relative to which the arms move. When the treadle 10 is thrown to its operative position the pivot 41 is lowered and the links 40 cause the arms 35 and 38 to assume vertically aligned positions with the result 70 that the plunger 16 is forced downwardly the necessary distance to produce the button forming operation. In thus operating the plunger care should be taken that the extremity of the downward movement of the 75 pivot 41 does not pass below a horizontal line connecting the center of said pivot with the pivots 37 and it is for this purpose that the movement of the treadle 10 is limited and made adjustable by the abutment 14. 80

It sometimes occurs that different sized dies are employed in connection with the machine which necessitates the regulation of the movement of the plunger 16, this being accomplished through an adjustment of 85 the operating mechanism for the plunger, and particularly the bearing 36 thereof. For this purpose the upper frame member 6 is provided with an opening 42 through which an adjusting screw 43 extends. This screw is held in position by means of the nuts 44 and 45 engageable, respectively, with the upper and lower surfaces of the frame member 6 and which nuts may be employed in a manner which is obvious to adjust the 90 height of the screw member 43. A bolt 46 is threaded into the lower end of the screw member and is utilized to hold the bearing 36 between the head of the bolt and the lower end of said screw member so as to 95 support the mechanism including the arms 35 and 38 in proper position. Thus it will be seen that by regulating the height of the screw member 43 the position of the toggle mechanism and of the plunger 16 may be 100 adjusted so that the extremity of downward movement of said plunger 16 may be regulated in order that the die will properly 105 form the button.

The means for supporting the ejector-operating rod 34 so as to properly position its lower end for contact with the ejector 32 consists of a bolt 47 threaded into the upper end of the screw 43 and having the upper end of the rod 34 connected thereto. Thus 110 by a manipulation of the bolt 47 the height of the rod 34, which extends through the bolt 46, may be regulated.

What is claimed is:

1. In a button-making machine, a frame, a die, a plunger carried by said frame for operating said die, means for applying pressure to said plunger including a supporting bearing, a plurality of pivotally connected toggle arms joining said bearing with said plunger, a screw member adjustable in said frame, a bolt threaded into said screw member longitudinally thereof and carrying said bearing in a fixed position between the same and said screw member, and means for ad- 120

125 130

justing the screw member relative to the frame to alter the effective movement of said plunger.

2. In a button-making machine, a frame, a die, a reciprocatory plunger carried by said frame for operating said die, means including a bearing for supporting said plunger, a screw member adjustable in said frame to vary the height of said bearing, a bolt carried by said screw member and engageable with said bearing to maintain the same in fixed position relative to said screw member, an ejector for ejecting a button from said

die, an ejector-operating rod extending through said bolt and into said screw member and having its lower end positioned adjacent said plunger so as to contact said ejector when the plunger is raised, and a bolt having threaded engagement with said screw member and to which said rod is connected whereby the same may be adjusted vertically and relative to said plunger. 15 20

In testimony whereof I have affixed my signature.

ALEXANDER HUREWITZ.
